Primary Examiner — Nicole C Shiflet*Assistant Examiner* — Bobby W Jones, II*(74) Attorney, Agent, or Firm* — Andrew C. Cheng(57) CLAIM

The ornamental design for a water filter as shown and described.

DESCRIPTION

FIG. 1 is a top perspective view of a water filter, showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the water filter that form no part of the claimed design.
